UNITED STATES PATENT OFFICE

HARRY S. THOMPSON, OF DETROIT, MICHIGAN

GARMENT

Application filed October 3, 1927. Serial No. 223,788.

This invention relates to garments and has as an object to provide a garment which will permit free movement of the body of the wearer without binding at any points whatever.

A further object of this invention is to provide a garment having complementary overlapping sections, which sections shall be freely movable with respect to each other so as to readily compensate for any movements of the body of the wearer.

Other objects and advantages of this invention will become apparent as the following description proceeds, particularly when reference is had to the accompanying drawings wherein

Figure 1 is a rear elevational view of a garment constructed in accordance with my invention showing the same as it appears when being worn.

Figure 2 is a view similar to Figure 1 of a slightly modified form of garment;

Figure 3 is a view similar to Figure 1 of a still further modification of the form which my invention may assume showing also the body of the wearer in a slightly different position; and

Figure 4 is an enlarged transverse sectional view taken on the line 4-4 of Figure 3.

Referring now particularly to the drawings wherein like reference characters designate corresponding parts throughout all views of the same, the numeral 10 designates generally the back of an under garment. The front of the garment is not shown since the same may be of any desired form and constitutes no part of the present invention.

It is to be understood, however, that while I describe my invention in connection with an under garment, the same may be embodied in a garment of any character and that the term "garment" as used refers to garments of any character.

As shown in Figure 1 of the drawing the back 10 of the garment is divided into two sections 11 and 12 respectively. While the front of the garment is not shown, for the reason that the same may be of any desired

character, it will be obvious by reference to Figure 1 that the section 11 is attached at its side to the right side of the front of the garment, while the section 12 is connected at its side to the left side of the front of the garment. The sections 11 and 12 are complementary to each other, being arranged in overlapping relation to each other as at 13 and are free to move with respect to each other either laterally or longitudinally.

The section 11, which as illustrated constitutes the right-hand section, is provided with a shoulder strap 14 while the section 12 which constitutes the left-hand section is provided with a shoulder strap 15. As also clearly illustrated in Figure 1 of the drawing, the shoulder straps 14 and 15 cross each other, the strap 14 from the right-hand section being adapted to pass over the left shoulder for connection to the left side of the front of the garment and the strap 15 from the left-hand section being adapted to pass over the right shoulder. The straps at their point of crossing are not secured to each other in any way whatever and are therefore also free to move with respect to each other.

From the above, it will readily be apparent that when the garment is worn any movement of one arm or one side of the wearer with respect to the other arm or to the other side, will immediately be compensated for by movement of one of the back sections and its respective shoulder strap with respect to the other back section and its shoulder strap. The garment will therefore find particular utility for wear during athletic contests wherein freedom of movement of the body is essential, although it is to be clearly understood that the garment is adapted for general wear. In addition to permitting free movement of the body of the wearer, it will be readily apparent that the garment will immediately adjust itself to any deformity in the body of the wearer so that the garment will fit correctly regardless of the physical characteristics of the person wearing the same.

While it is preferable to have the sections

of the back freely movable with respect to each other throughout their entire length, it may be desirable to attach the sections to each other at a point intermediate their length to cause the garment to fit more snugly. To accomplish this without greatly decreasing the freedom of movement between the sections of the back, I provide the arrangement illustrated in Figure 2 wherein the back is divided into two independent sections 11' and 12', which sections are overlapped as at 13' and are provided with the shoulder straps 14' and 15' respectively. The sections 11' and 12' are attached to each other by a tape 16, this tape being secured to the section 12' as by the stitching 17 and being extended for detachable engagement with a button 18 carried by the section 11'. As illustrated, I prefer to locate this tape at a point substantially near the middle of the back whereby free movement of the sections of the upper portion of the back will not be hindered. It will readily be apparent that the upper sections of the back will be free to move laterally inasmuch as they may pivot about their points of attachment to the tape. Further by using a tape, I provide for a slight relative longitudinal movement of the two sections of the back this being permitted by slight movements of the tape. In this way it will be seen that I provide for effecting a snug fit of the garment without materially reducing the free movement of the sections of the back with respect to each other.

In Figure 3 I have shown still another means for effecting a snug fit of the garment. In this form of my invention the sections 12² and 11² are provided with tapes 19 and 20 which attach the sections of the back together in a manner similar to the tape 16, but which differ from the tape 16 in that they are elastic. More particularly the tape 19 is sewed at 21 to one edge of the section 12² and is sewed at 22 to an adjacent point on the section 11². The elastic tape 20 is arranged on the inner side of the garment and is stitched as at 23 to the section 11² and as at 24 to the section 12². The elastic tapes will permit relatively free movement of the sections of the back while holding the said sections in juxtaposition with respect to each other. Further these elastic tapes will permit free opening of the back of the garment since they may be stretched to permit a folding back of the overlapping sections of the garment.

While I have shown several forms which my invention may assume, it is to be noted that all of the forms include complementary portions relatively freely movable with respect to each other. It will therefore be apparent that when the garment is worn, any movement of the body of the wearer will be freely permitted by movement of

one of the sections relative to the other and that this movement may be either lateral or longitudinal.

While I have shown my invention as being embodied in the back of an undergarment, it will be readily apparent that the same may be embodied in various parts of different garments. I therefore reserve the right to make such changes in the details of construction and arrangement of parts as will fall within the purview of the attached claims.

What I claim as my invention is:

1. In an undergarment, a back formed of two sections which are freely movable relative to each other in longitudinal and transverse directions to compensate for any movements of the body of the wearer, each section extending from one side of the garment toward the opposite side and terminating in a free edge beyond the middle of the back whereby the sections form opposite sides of the back, the free edge of each section slightly overlapping the free edge of the other section throughout substantially its entire length, and being spaced a substantial distance from the opposite side, and shoulder straps carried by said sections, each shoulder strap extending over the shoulder opposite to the side formed by its respective section.

2. In an undergarment, a back formed of two sections which are freely movable relative to each other in longitudinal and transverse directions to compensate for any movements of the body of the wearer, each section forming one leg portion of the back and a side portion corresponding to said leg portion and each section extending from one side of the garment towards the opposite side thereof and terminating in a free edge beyond the middle of the back whereby the sections form opposite sides of the back, the free edge of each section extending from the shoulder of the garment to the crotch thereof, and each free edge slightly overlapping the free edge of the other section throughout substantially its entire length and being spaced a substantial distance from the opposite side, and shoulder straps carried by said sections, each shoulder strap extending over the shoulder opposite to the side formed by its respective section.

3. In an undergarment, a back formed of two sections which are freely movable relative to each other in longitudinal and transverse directions to compensate for any movements of the body of the wearer, each section extending from one side of the garment toward the opposite side and terminating in a free edge beyond the middle of the back whereby the sections form opposite sides of the back, the free edge of each section slightly overlapping the free edge of the other section throughout substantially its

entire length and being spaced a substantial distance from the opposite side, shoulder straps carried by said sections, each shoulder strap extending over the shoulder opposite to the side formed by its respective section, and means loosely connecting the free edge of one of said sections to the other of said sections at a point intermediate the ends of said free edge to hold said sections in juxtaposition to each other while permitting longitudinal and lateral movement of said sections relative to each other.

In testimony whereof I affix my signature.
HARRY S. THOMPSON.
